UNITED STATES PATENT OFFICE.

EDWARD G. NIKLAUS, OF MADISON, INDIANA.

DESIGN FOR A BUTTON.

SPECIFICATION forming part of Design No. 24,790, dated October 29, 1895.

Application filed August 8, 1895, Serial No. 558,683. Term of patent 3½ years.

To all whom it may concern:

Be it known that I, EDWARD G. NIKLAUS, of Madison, county of Jefferson, State of Indiana, have invented and produced a new and original Design for Buttons, of which the following is a specification, reference being had to the accompanying drawings.

In the accompanying drawings, Figure I is a top plan view of my button on a magnified scale. Fig. II is a central vertical section thereof.

Referring to the figures on the drawings, 1 indicates a disk-shaped button provided with a circular bead 4 adjacent to its periphery and 15 with a milled edge 5.

6 indicates a bead of a smaller diameter than the bead 4, but concentric therewith, and 7 indicates a representation of a bug within the bead 6.

The button described is intended to be fastened in use by a suitable or ordinary means—as, for example, the shank 2 and base 3 illustrated; but my design has reference solely to the configuration and ornamentation of the button proper. 20

What I claim is—

The design for a button herein shown and described ornamented by the concentric beads 4 and 6 and the representation of a bug within the bead 6, substantially as specified. 25

In testimony of all which I have hereunto subscribed my name.

EDWARD G. NIKLAUS.
